[57] **CLAIM**

The ornamental design for a bipod for supporting a firearm, as shown and described.

DESCRIPTION

FIG. 1 is a top plan view of one embodiment of a bipod for supporting a firearm, showing my new design;

FIG. 2 is a front elevational view thereof;

FIG. 3 is a bottom plan view thereof;

FIG. 4 is a side elevational view thereof, with both of two side views being identical;

FIG. 5 is a rear elevational view thereof;

FIG. 6 is a top plan view of another embodiment of a bipod for supporting a firearm, showing my new design;

FIG. 7 is a front elevational view of the design shown in FIG. 6;

FIG. 8 is a bottom plan view of the design shown in FIG. 6;

FIG. 9 is a side elevational view of the design shown in FIG. 6, with both of two side views being identical; and,

FIG. 10 is a rear elevational view of the design shown in FIG. 6.
